(57) **CLAIM**

The ornamental design for a razor, as shown and described.

DESCRIPTION

The file of this patent contains at least one drawing executed in color. Copies of this patent with color drawings will be provided by the Office upon request and payment of the necessary fee.

FIG. 1 is a front view of a first embodiment of a razor, showing my new design;

FIG. 2 is a rear view of the first embodiment;

FIG. 3 is a left view of the first embodiment;

FIG. 4 is a right view of the first embodiment;

FIG. 5 is a top view of the first embodiment;

FIG. 6 is a bottom view of the first embodiment;

FIG. 7 is a perspective view of the first embodiment;

FIG. 8 is a front view of a second embodiment of a razor, showing my new design;

FIG. 9 is a rear view of the second embodiment;

FIG. 10 is a left view of the second embodiment;

FIG. 11 is a right view of the second embodiment;

FIG. 12 is a top view of the second embodiment;

FIG. 13 is a bottom view of the second embodiment; and,

FIG. 14 is a perspective view of the second embodiment.
